UNITED STATES PATENT OFFICE

GEOERGE L. CURLE, OF MINNEAPOLIS, MINNESOTA

DESIGN FOR A MATRIX ANVIL

Application filed January 20, 1932. Serial No. 42,564. Term of patent 3½ years.

To all whom it may concern:

Be it known that I, GEORGE L. CURLE, a citizen of the United States, residing at Minneapolis, in the county of Hennepin and State of Minnesota, have invented a new, original, and ornamental Design for a Matrix Anvil, of which the following is a specification, reference being had to the accompanying drawings, forming part thereof.

Fig. 1 is a perspective view of the matrix anvil, showing my new design; and Fig. 2 is a rear perspective view thereof.

I claim:

The ornamental design for a matrix anvil, substantially as shown.

GEORGE L. CURLE.
